UNITED STATES PATENT OFFICE.

JOHN C. BARBER, OF CHICAGO, ILLINOIS.

CAR-TRUCK.

1,347,887.

Specification of Letters Patent. Patented July 27, 1920.

Application filed November 10, 1919. Serial No. 336,917.

To all whom it may concern:

Be it known that I, JOHN C. BARBER, a citizen of the United States, residing at Chicago, in the county of Cook and State 5 of Illinois, have invented certain new and useful Improvements in Car-Trucks; and I do hereby declare the following to be a full, clear, and exact description of the invention, such as will enable others skilled 10 in the art to which it appertains to make and use the same.

My present invention relates to car trucks and is directed, particularly, to the improvement of six wheeled trucks wherein the 15 bolsters, or bolster structure, is mounted for lateral motion.

Generally stated, the invention consists of the novel devices and combinations of devices hereinafter described and defined in 20 the claims.

In this improved truck, by a novel arrangement of springs, journal boxes and bolster structure, I provide an arrangement wherein the load will be equalized without 25 the use of what are usually known as equalizers, and which, in the usual six-wheeled truck, are additional independently formed equalizing levers; and by this novel arrangement, I greatly simplify the truck structure.

As further important features, I make the journal boxes counterparts, one of the other, so that they may be interchangeably used, and also, make the springs alike or counterpart so that they may also be interchangeably used. The invention, however, involves 35 certain other novel features, as will hereinafter appear. The invention is illustrated in the accompanying drawings wherein like characters indicate like parts throughout 40 the several views.

Referring to the drawings:

Figure 1 is a plan view of the improved truck;

Fig. 2 is a side elevation of the truck;

Fig. 3 is a transverse section taken approximately on the irregular line 3-3 of Fig. 1;

Fig. 4 is a horizontal section taken approximately on the irregular line 4-4 of Fig. 2; and

Fig. 5 is a fragmentary section on the line 5-5 of Fig. 3.

The outside or end wheels 6 of the truck are secured in the customary way to axles 55 7, while the intermediate or central wheels

8 are, likewise, secured to an axle 9. The ends of the several axles 7 and 9 are journaled in journal boxes 10 that are all alike, so that they may be interchangeably used, and any box may be applied to any axle, and 60 if cast, all of the boxes may be cast from the same pattern.

The truck side frames 11 are here shown as one piece cast steel with three openings 12 for the journal boxes and two additional 65 openings 13 for the ends of the two bolsters here employed. The outside openings 12 for the end journal boxes are between pedestals 14, while the central openings 12 are between pedestals 14^a. The said openings 12 70 extend to the bottom of the laterally spaced depending flanges or webs 11^a of the side frame 11 and these gaps are normally closed by bridge bars 15 rigidly bolted to the lower ends of the adjacent pedestals. 75

The pedestals are capable of vertical movements in channels formed in the sides of the journal boxes 10 between laterally spaced outstanding stop flanges or shoulders 16. On the several boxes, the spacing between flanges 16 is the same, and the width of the end pedestals 14 is such that the end journal boxes will have little or no movement transversely of the truck. The width of the intermediate pedestals 14^a, however, is 80 less than that of the pedestals 14, so that there will be clearance between the same and the stop flanges 16 on the intermediate or central journal boxes (see particularly Fig. 1), and this, as is obvious, will permit 85 movements of the central journal boxes transversely of the truck, as required when the truck is traveling curves. The above noted lateral movement of the central journal boxes and wheels, it will be understood, 90 is independent of the lateral motion between the car body and the truck provided for, as presently to be described. 95

Above, and at the sides of the bolster passages 13, the two side frames 10 are rigidly 100 fastened together by rectangular double transoms 18, so that the truck frame made up of the said side frames and transoms is a rigid structure.

The truck bolsters 19 are capable of both 105 vertical and endwise movements in the above noted bolster passages in the side frames 11, and, as shown, they are provided with stop lugs 20 that engage angular tie plates 21 of the respective transoms 18 110

to limit the endwise movements of the said bolsters transversely of the truck. Otherwise stated, the stop lugs 20 limit the lateral motion proper of the truck frame in respect to the car body, or conversely, the car body in respect to the truck frame.

The transoms are preferably provided with brake hanger lugs 22, and the ends of the side frames are turned inward and provided with brake hanger lugs 23 arranged to support brake shoes, not shown, for engagement with both sides of the several truck wheels.

The two bolsters 19 are tied together for common lateral movements, that is, common endwise movements transversely of the truck, preferably by an H-shaped bolster tie frame which is indicated as an entirety by the numeral 24, and, at its central portion, carries a center bearing 25 for coöperation with a center bearing not shown but which will be located on the truck body in the usual or any suitable manner.

The truck side frames are carried from the journal boxes through interposed springs and self-centering lateral motion devices, preferably coöoperating rollers and concave seats, are interposed, also between the central transversely or laterally movable journal boxes and the side frames. Springs and self-centering lateral motion bearing devices also support the bolsters from the side frames and these latter are preferably of the character disclosed and broadly claimed in my prior Patent 1,316,553, the same being here brought into a new and important coöoperative relation to the main elements of a six-wheeled car truck.

The springs above just referred to are preferably all coiled springs made, all exactly alike, both in respect to normal length and strength. Those springs that are employed to carry the truck frame from the journal boxes are indicated by the numeral 26 and those springs that are used to support the bolsters 19 from the side frame are indicated by the numeral 27. The springs 26 are shown as arranged in groups of two, their upper ends being seated in the channels of the side frames 11. The end groups 26 are seated around bosses 28 formed on the tops of the journal boxes.

Between the bottoms of the central group of springs 26 and the central journal boxes, self-centering lateral motion devices comprising spring bases 29, roller bases 30 and interposed rollers 31 are placed; and to provide additional space for such lateral motion devices (see Figs. 2 and 5), the side frames are raised or increased in vertical section at their central portions.

The spring bases 30 have seats that fit the bosses 28 on the tops of the journal boxes, and the spring bases 29 are provided

with corresponding bosses 32 that telescope into the lower ends of the central springs 36.

The lateral motion devices that support the bolsters 19, as preferably constructed, comprise spring bases 33, roller bases 34 and interposed rollers 35, (see particularly Figs. 2 and 4). The roller bases 34 are cast integral with tie bars 37, the ends of which are interposed between the depending ends of the bolster columns or pedestals 13^a and 75 are detachably secured thereto by coupling pins 38 shown as held in position by keys or cotters 39. The bolster supporting springs 27 are interposed between the spring bases 33 and overlying ends of the respective truck bolsters 19. The above noted spring plates or bases 33 and roller bases 34 are formed with the customary concave roller-engaging seats, preferably such as generally employed in the well known Barber lateral motion trucks. Substantially the same statement is true in respect to the previously described spring bases 29 and roller bases 30.

As shown and preferred, the spring bases 33 are cast or formed integral with and constitute the ends of transverse spring planks 40, which, at their central points, have upstanding studs 41 that fit seats in the central lower portions of the respective bolsters 19, so that the bolsters and spring planks must move together transversely of the truck.

In the above described arrangement, the springs between the side frames and journal boxes and between the side frames and bolsters will take care of all irregularities in the track and substantially equalize the load in the various springs or spring groups. When the tie bars 15 and 27 are applied, 100 they give very great rigidity to the lower portions of the side frame, but when removed they permit, in the one instance, the journal box to be removed from the side frames, and in the other instance, the truck 110 bolsters and spring planks to be removed.

The lateral motion devices between the side frames and bolsters take care of lateral forces transmitted from the car body to the car truck, or vice versa, while the lateral motion devices between the central journal boxes and the side frames permit the required lateral movements of the central wheels in traveling curves and on straight track yieldingly hold the center wheels in 120 intermediate positions alined with the front and rear wheels.

Six-wheeled trucks embodying my invention above disclosed may be used, both in passenger and in freight service.

What I claim is:

1. In a car truck, the combination with end and intermediate wheels and a truck frame, said intermediate wheels being mounted for lateral movements in respect to 130

- the truck frame and end wheels, of a bolster structure carried by said truck frame, and lateral motion devices permitting lateral movements of said bolster structure independently of the lateral movements of said intermediate wheels and in respect to the truck frame.
2. In a car truck, the combination with end and intermediate truck wheels, their axles and journal boxes on said axles, of connected truck side frames spring supported on the end of intermediate journal boxes, lateral motion devices permitting lateral movements of said intermediate wheels and their journal boxes, connected truck bolsters spring-supported from said side frames, and lateral motion devices permitting lateral movements of said truck bolster independently of the lateral movements of said intermediate truck wheels and their journal boxes.
3. In a car truck, the combination with end and intermediate truck wheels, their axles and journal boxes on said axles, of connected truck side frames spring supported on the end of intermediate journal boxes, lateral motion devices permitting lateral movements of said intermediate wheels and their journal boxes, connected truck bolsters spring-supported from said side frames, and lateral motion devices permitting lateral movements of said truck bolster independently of the lateral movements of said intermediate truck wheels and their journal boxes, the connections between said truck bolster having a centrally located center bearing.
4. In a car truck, the combination with end and intermediate wheels, their axles and journal boxes on said axles, truck side frames, connected truck bolsters extended through said side frames, springs interposed between said end and intermediate journal boxes and side frames to support the latter, end springs interposed between said side frames and bolsters, all of said springs being counterparts, so that they may be interchangeably used or applied, lateral motion devices interposed between the center journal boxes and side frames, and lateral motion devices interposed between said side frames and bolsters.
5. In a car truck, the combination with end and intermediate truck wheels, their axles and journal boxes on said axles, of connected truck side frames having seats for said journal boxes and movable vertically thereon, springs supporting said side frames from said journal boxes, said side frames between said journal boxes having bolster passages, connected truck bolsters mounted for vertical and limited endwise lateral movements in said bolster seats, roller bases supported at the bottoms of said bolster passages, rollers thereon, spring planks connected to move transversely with the respective bolsters and, at their ends, having spring bases seated on the respective rollers, and springs interposed between said spring bases and the ends of the overlying bolsters.
6. In a car truck, the combination with end and intermediate truck wheels, their axles and journal boxes on said axles, of connected truck side frames having seats for said journal boxes and movable vertically thereon, springs supporting said side frames from said journal boxes, said side frames between said journal boxes having bolster passages, connected truck bolsters mounted for vertical and limited endwise lateral movements in said bolster seats, roller bases supported at the bottoms of said bolster passages, rollers thereon, spring planks connected to move transversely with the respective bolsters and, at their ends, having spring bases seated on the respective rollers, and springs interposed between said spring bases and the ends of the overlying bolsters, and bridge bars detachably applied to said side frames below said bolster passages and directly supporting the corresponding roller bases, said roller bases and spring bases having coöperating concave self-centering roller-engaging surfaces.

In testimony whereof I affix my signature in presence of two witnesses.

JOHN C. BARBER.
